PHONOGRAPH ATTACHMENT

Helena Zurstadt, Baltimore, Md.

Application March 28, 1942, Serial No. 436,661

1 Claim. (Cl. 274—1)

The invention relates to a phonograph attachment constituting a record theme guide.

The object of the present invention is to provide for phonographs an attachment adapted to be arranged directly upon the top of a rotating sound record disk of a musical composition and extending from the center to the periphery thereof and provided with a plurality of straight needle receiving slots extending radially across grooves of the sound record disk and permitting the needle of the tone arm of the phonograph to extend through them and operate in the grooves of the sound record and play selected portions of a symphony or other musical composition to enable a lecturer or an individual student of music in a course of musical instruction to make an analysis of a musical composition such as a symphony and isolate and play the introduction, the numerical succession of the themes, the episode, the coda, link passages, recapitulation and other musical features of the sections of the movements of a recorded symphony by simply placing the needle of the tone arm of the phonograph in slots of the record disk or phonograph attachment and playing the desired isolated portions of the sound recordings.

A further object of the invention is to provide for phonographs a disk attachment of a size substantially coextensive with a musical sound record disk and having a central circular opening to receive the spindle of the turntable of the phonograph and divided into sector-shaped areas, each associated with one of the movements of a symphony and with a sound record thereof and provided with musical feature needle receiving slots, whereby the disk of the present invention will isolate sections of the sound record and enable a lecturer to make a complete analysis of an entire symphony by means of a single record disk attachment, if the symphony is not of unusual length, it being only necessary to change the sound records of the recorded symphony and place the needle of the tone arm in the different slots of the device of the present invention.

With these and other objects in view the invention consists in the novel construction, combination and arrangement of parts hereinafter fully described, illustrated in the accompanying drawing and pointed out in the claim hereto appended, it being understood that various changes in the form, proportion, and minor details of construction, within the scope of the claim, may be resorted to without departing from the spirit or sacrificing any advantages of the invention.

In the drawing the figure is a plan view of a

disk adapted to be placed on top of a phonograph sound record and constructed for analyzing Beethoven's Symphony No. 1.

Referring to the drawing, in which is illustrated one embodiment of the invention, 1 designates a disk-shaped member consisting of a disk of thin sheet material and preferably of a size sufficient to cover substantially a sound record and adapted in use to be placed upon the top of the same when the sound record is arranged on the turntable of a phonograph for playing in the usual manner. Any suitable thin sheet material may be used; drawing paper has been found very satisfactory for making record disks, as it is sufficiently thin and possesses the necessary stiffness. As the disk attachment is placed directly on top of and is supported by a sound record disk comparatively light sheet material may be used.

The disk, which is provided with a central spindle receiving opening 2, is constructed for analyzing Beethoven's Symphony No. 1, recorded on Victor records Nos. 7211 to 7214, inclusive, and composed of four movements, each recorded on one of the said Victor records. The disk 1 is divided by four radial full lines 3 into four sector-shaped areas 4, 5, 6 and 7 or segments which are subdivided by broken lines 8 into sector-shaped sections 9. Each of the sector-shaped areas 4, 5, 6 and 7 provides ample space for the needle receiving slots, hereinafter specifically referred to, for isolating the musical features of one movement of the musical composition and the sector-shaped sections 9 of the area 4, 5, 6 and 7 contain the needle receiving slots of the different sections of each individual movement. In other words, each sector-shaped area covers one movement of the symphony and the subdivisions 9 thereof cover the different sections of each movement. The full lines 3 preferably extend from the periphery of the disk to the central opening 2 thereof while the broken lines terminate short of the center of the disk, but the divisions of the disk 1 may be indicated in any other desired manner.

The four main divisions cover the four movements of the symphony. The first sector-shaped area 4 covering the first movement of the symphony is provided with three subdivisions. The first subdivision containing the needle receiving slots 10, 11, 12, 13, 14, 15, 16, 17 and 18 is entitled "Exposition," and is the first section of the first movement of the symphony. The slot 10 isolates the introduction, slot 11 theme No. 1, slot 12 the episode, slot 13 theme No. 2, slot 14 extension theme No. 2, slot 15 closing theme, slot 16

the coda, slot 17 exposition repeated, and 18 the conclusion of the exposition.

The second subdivision is entitled "Development" and will contain appropriately arranged slots for isolating the musical features of the 5 second section of the first movement of the symphony.

The third subdivision entitled "Recapitulation" will be provided with appropriately arranged slots for isolating the musical features of the third 10 section of the first movement of the symphony.

The second, third and fourth sector-shaped areas 5, 6 and 7 will be subdivided as indicated by the broken lines 3 which in practice may be solid red lines or lines of any other distinguishing character and the subdivisions will be provided with slots appropriate to the sections of the second, third and fourth movements of the symphony.

The slots are straight and are radially arranged and when the disk attachment is placed upon the top of a sound record and the needle of the tone arm of the phonograph is placed in one of the slots it will operate in the ordinary manner in the grooves traversed and exposed by said slot. While any ordinary needle may be used it is preferable to use a needle having a floating point, and sold on the market under the Trade-Mark "Fidelitone," as it has been found that such needle will not injure the end walls of the slots 25 of a thin paper disk.

It will be seen that when the record disk is arranged upon a sound record with the spindle of the turntable extending through the central opening 2 and the needle of the tone arm of the phonograph placed in one of the slots, the record disk 1 will remain stationary and the sound record disk will rotate with the turntable. The needle is placed in the slot at the outer end thereof and will continue playing the record until it reaches the inner end of the slot and when the tone arm is removed, the playing will cease. The slot isolates the desired section of the phonograph recording, and the straight radial slots 30 may be of any desired length for isolating any 35 desired sections of a musical composition or other

matter recorded on a phonograph sound record. The needle may be readily transferred from one slot to another without removing the record disk from the sound record.

While the record disk 1 shown in the drawing is adapted to analyzing and explaining a symphony, it will be apparent that the slots may be arranged for isolating the musical features or distinguishing characteristics of any other form 15 of musical composition and will enable the layman to study the form or construction of the composition through the use of a phonograph record and a miniature orchestral score or a form outline that links the phonograph record and the disk.

What is claimed is:

A phonograph attachment constituting a record theme guide for analyzing musical compositions for imparting musical instruction and consisting of a disk of thin sheet material of substantially the size of a sound record and provided with a central opening to receive the spindle of the turntable of a phonograph and adapted to be placed upon the top of a sound record, said disk being divided into a plurality of sector shaped segments and provided in said segments with straight radial slots circumferentially spaced and having a combined length to traverse substantially all of the convolutions of the spiral groove of a sound record and each segment adapted to isolate a different portion of a musical composition, the individual slots spanning a portion of a musical composition such as the introduction, theme No. 1, the episode, theme No. 2, the closing theme, the coda, the repeated exposition and the conclusion of the exposition and said slots being arranged to receive the needle of the tone arm of a phonograph whereby the disk will be held stationary while playing a section of a second record, the various slots permitting the needle to be placed in them without removing the disk from the sound record to play successively and repeatedly all of the isolated portions of the sound record.
